(57) **CLAIM**

The ornamental design for a socket, as shown and described.

DESCRIPTION

FIG. 1 is a front perspective view of a socket showing my new design;

FIG. 2 is a front view thereof;

FIG. 3 is a top view thereof;

FIG. 4 is a bottom view thereof;

FIG. 5 is a rear view thereof;

FIG. 6 is an A-A cross-section view thereof; and,

FIG. 7 is a B-B cross-section view thereof.

The bottom face of the socket hole of my new design having the unclaimed square hole is a uniformed surface without folding line or corner, and is inclined toward the center of the bottom face.

The broken lines represent unclaimed portions of the design article. All of the broken lines forms no part of the claimed design.
